PURIFICATION OF BENZENE

Ernest Carlton Housam and Ronald Lester, Sunbury-on-Thames, England, assignors to The British Petroleum Company Limited, London, England, a British joint-stock corporation

No Drawing. Filed July 9, 1957, Ser. No. 670,666

Claims priority, application Great Britain July 11, 1956

5 Claims. (Cl. 260—674)

This invention relates to the purification of benzene, and particularly to the production of nitration grade benzene.

It is well known that it is difficult to separate benzene from non-aromatic hydrocarbons by simple fractional distillation owing to the formation of azeotropes. It is particularly a problem in the production of nitration grade benzene from certain crude benzoles, since these latter contain a proportion of paraffins and naphthenes which are not separable by simple fractional distillation. In consequence the product fails to pass the stringent requirements of crystallisation point and specific gravity set down for nitration grade benzene. In addition nitration grade benzene must satisfy other requirements such as distillation range, carbon disulphide and thiophene content. Full details of the nitration grade benzene specification are given in British Standard Specification 135:1953, "Benzoles."

According to the present invention benzene is separated from mixtures of benzene and non-aromatic hydrocarbons which form azeotropes with the benzene by subjecting the mixture to catalytic reforming and fractionally distilling the reformed product to obtain a benzene fraction. The term "benzene fraction" is to be understood to mean a fraction rich in benzene but not excluding minor proportions of other hydrocarbons. The preferred benzene fraction is one passing the nitration grade benzene specification.

The catalytic reforming step converts part of the non-aromatic hydrocarbon content to additional benzene and the remainder to compounds from which benzene can be separated by simple fractional distillation. As mentioned above, the process is applicable to the production of nitration grade benzene from crude benzole, for example gas works benzole. Such benzoles also contain sulphur and nitrogen compounds so that these and other sulphur containing feedstocks require desulphurising in addition to reforming.

This desulphurisation is preferably carried out simultaneously with the reforming in a single-stage catalytic reforming and hydrodesulphurisation treatment, by selecting a sulphur-resistant catalyst having both reforming and desulphurising properties, for example a catalyst containing the oxides of cobalt and molybdenum (either as such or as cobalt molybdate or both) supported on alumina. Alternatively the feedstock may be hydrodesulphurised or acid treated prior to the catalytic reforming in which case the reforming catalyst need not be sulphur-resistant—it may be for example a catalyst of platinum on a support such as alumina.

The conditions for the catalytic reforming, whether

with simultaneous hydrodesulphurisation or not, are preferably selected from the following ranges:

Pressure ..... 50-1000 p.s.i.g.
Temperature ..... 850°-1050° F.
Space velocity ..... 0.5-5 v./v./hr.
Gas rate ..... 0.5-15/1 molar hydrogen/hydrocarbon ratio.

The precise operating conditions used will depend on the characteristics of the feedstock, for example the relative proportion of non-aromatic hydrocarbons to benzene and experiments may be necessary to determine the optimum operating conditions for any given feedstock.

The subsequent fractional distillation should preferably be such as to obtain a narrow benzene heart cut, particularly if nitration grade benzene is required.

The invention is illustrated by the following examples.

Example 1

A Barbet benzene, that is a distillate from gas works crude benzole containing over 90% of benzene, was hydrofined under the following operating conditions. It is readily apparent that the crude benzole contained a major portion of benzene.

Catalyst ..... Cobalt and molybdenum oxides on alumina.
Pressure ..... 300 p.s.i.g.
Temperature ..... 720° F.
Space velocity ..... 1.0 v./v./hr.
Gas rate ..... 1000 s.c.f./b.
Make up gas ..... Pure hydrogen.

The hydrofined product was distilled in a 14 plate column at a reflux ratio of 15:1 to give a benzene heart cut, but this heart cut was found to have a specific gravity below the limits specified for nitration grade benzene (0.883-0.886). The inspection data were:

	Feedstock	Total hydrofined product	Hydrofined benzene heart cut
Specific gravity, 60° F./60° F.	0.8785	0.8730	0.8780
Sulphur, percent wt.	0.424	0.005	0.0002

This benzene heart cut was then catalytically reformed under the following conditions:

Catalyst ..... Platinum on alumina.
Pressure ..... 250 p.s.i.g.
Temperature ..... 940° F.
Space velocity ..... 1.0 v./v./hr.
Gas rate ..... 1/1 mol H₂/hydrocarbon ratio.

The resulting reformat was distilled in a 20 plate column at a reflux ratio of 20:1 to give a benzene heart cut. This cut met all the requirements of the National Benzole Association nitration grade benzene specification as follows:

Test	Nitration grade benzene specification	Catalytically reformed benzene heart cut
Specific gravity at 15.5° C./15.5° C.	0.883-0.886	0.8835.

FBP.....° C.			80.4.	
Recovery.....percent vol.			99.	
Residue.....do			0.5.	
Loss.....do			0.5.	
Total sulphur.....percent wt.	0.424	0.007	<0.0003	Not more than 0.035.
Sulphur as carbon disulphide.....do			0.00025.	Not more than 0.01.
Sulphur as thiophene.....do			5.2.	Not below 5.0.
Crystallization point.....° C.			1.	Not greater than 5.
Residue on evaporation.....mg./100 ml.			Freed from undissolved water and other separated impurities.	Freed from undissolved water and other separated impurities at 15.5° C.
Water.....			Paler than standard.	Paler than a standard solution.
Acid wash test.....			do	Do.
Colour.....			Doctor negative.	Negative to doctor test.
H ₂ S and mercaptans.....			Slightly alkaline.	Must not give an acid reaction with the National Benzole Association mixed indicator.

crude benzole containing over 90% of benzene, was treated under the following operation conditions:

Pressure ..... 700 p.s.i.g.
Temperature ..... 940° F.
Space velocity ..... 0.5 v./v./hr.
Gas rate ..... 4000 s.c.f./b.
Make-up gas ..... Pure hydrogen.

The catalyst consisted of 2.9% by weight of cobalt oxide and 15.6% by weight of molybdenum oxide supported on activated alumina, both percentages based on the weight of the catalyst.

The reformed and desulphurised product was fractionally distilled in a 20 plate column at a reflux ratio of 20:1 to give a benzene heart cut.

Inspection data on the feedstock, the reformed product and the benzene heart cut, and the National Benzole

It will be seen that the heart cut from the reformed and desulphurised product met all the requirements for nitration grade benzene.

We claim:

1. In a method of separating benzene from crude benzole mixtures comprising benzene and non-aromatic hydrocarbons which form azeotropes with the benzene, and sulphur compounds, said mixtures containing a major portion of benzene, and said method including the step of desulphurising the mixture, the improvement which comprises subjecting the mixture to catalytic reforming by contacting the mixture in the presence of added hydrogen with a reforming catalyst at a pressure in the range of 50 to 100° p.s.i.g., a temperature in the range of from 850° F. to 1050° F., a space velocity in the range of from 0.5 to 5 v./v./hr. and a molar hydrogen/hydrocarbon ratio in the range of from 0.5:1 to 15:1, and frac-

tionally distilling the reformed desulphurised product to obtain a benzene fraction.

2. A method as claimed in claim 1, wherein the mixture is simultaneously catalytically reformed and hydrodesulphurised by the use of a sulphur-resistant catalyst having both reforming and desulphurising properties.

3. A method as claimed in claim 2, wherein the catalyst comprises the oxides of cobalt and molybdenum supported on alumina.

4. A method as claimed in claim 1, wherein the mixture is treated prior to the catalytic reforming to desulphurise it.

5. The method of claim 4 wherein the catalytic reform-

ing of the desulphurised mixture is carried out in the presence of a catalyst of platinum supported on alumina.
